UNITED STATES PATENT OFFICE.

SAMUEL CARL STIMSON, OF LEWISVILLE, NORTH CAROLINA, ASSIGNOR OF ONE-HALF
TO WILLIAM WALKER SMOAK, OF WINSTON-SALEM, NORTH CAROLINA.

HAME FASTENER.

1,407,495.

Specification of Letters Patent. Patented Feb. 21, 1922.

Application filed April 15, 1921. Serial No. 461,710.

To all whom it may concern:

Be it known that I, SAMUEL C. STIMSON, a citizen of the United States, residing at Lewisville, in the county of Forsyth and State of North Carolina, have invented certain new and useful Improvements in Hame Fasteners; and I do declare the following to be a full, clear, and exact description of the invention, such as will enable others skilled in the art to which it appertains to make and use the same.

This invention relates to an improved hame fastener, and it has for its principal object to provide a device of this class which is an improvement on similar patented fasteners now patented or in common use, the same being such in construction that it becomes a permanent part of the hame, thus preventing it from dropping off of the latter and becoming lost or displaced as is the case of most fasteners now used.

Another object of the invention is to provide a hame fastener which is composed of two resilient hooks for connection to the usual loops on the lower end of the hame sections, these hooks having connected therewith a short length of strap and a buckle for co-action with the latter, thus rendering the fastener extremely simple in construction so that it can be manufactured and sold at an extremely low cost.

Other objects and advantages of the invention will be apparent during the course of the following description.

In the accompanying drawings forming a part of this specification and in which like numerals are employed to designate like parts throughout the same:

Figure 1 is an elevational view of the lower portion of a horse collar having a hame thereon equipped with a novel fastener constructed in accordance with this invention.

Figure 2 is an enlarged central longitudinal central view of the fastener showing the construction and arrangement of parts more clearly.

Figure 3 is a bottom plan view thereof.

Figures 4 and 5 are detailed perspective views of the novel hooks which the fastener includes.

Referring to the drawings in detail, the

numeral 1 designates a short leather strap equipped with a link 2 carrying a hook 3 for connection with the usual pivoted loop B on the lower end of the hame section A. The hook 3 could be of any other construction, however, I prefer to form it from a single length of resilient metal. In carrying this out, I pass the metal through the link 2 and bend it between its ends as indicated at 4 around the link, extending the ends thereof beyond the latter and bringing them into contact with one another as shown, thus providing a resilient two-ply piece 65 which is in turn bent between its ends as indicated at 6 to form the aforesaid hook 3. The hook thus formed provides a pocket 8 for reception of the loop B. At this point, attention is directed to the fact that the free 70 end of the hook is bent intermediate its ends as indicated at 9 to form what may be termed a transverse rib, this construction serving to provide a restricted entrance portion for the pocket 8. The extremity of said free end 75 of the hook is flared as indicated at 10 to facilitate engagement of the hook with the aforesaid loop B.

The invention in addition to embodying the aforesaid parts, includes a conventional 80 buckle 11 for co-action of the strap 1, this buckle carrying a second hook 12 which is constructed somewhat like the one already described. In support of the foregoing statement, it is to be stated that the hook 85 12 is formed from a single strip of resilient metal passed through and bent around a portion of the buckle as indicated at 13 its ends being brought together and in contact with one another to provide a two-ply member 90 bent upon itself to form a substantially U-shaped hook already indicated by the numeral 12. This hook 12, is, like the one already described, provided with a pocket 14 for reception of the pivoted loop C on the 95 hame-section D and it likewise has its entrance portion restricted by bending the free end of the hook inwardly as indicated at 15. The extremity of this hook is likewise flared outwardly as indicated at 16 but instead of 100 extending beyond the portion 13 as in the case of the first described hooks, it terminates at a point substantially above said portion 13. Hook 12 is equipped with a guide

ring or loop 17 for passage of the free end of the strap 1. This ring is positioned between the plies of the metal strip and the latter are bent around the adjacent horizontal portion of the ring as indicated at the points 18. It is to be noted that the inner bend 18 is directly opposite the bend 15 of the hook, thus additionally restricting the size of the entrance of the pocket 14. It 10 may be also pointed out here that the portion 4 of the hook 3 is directly opposite the bend 9 of the last named hook for the same purpose.

As seen in the drawing, the hook 12 is 15 engaged with the loop C while the hook 3 is engaged with the remaining loop B of the hame section. It is to be noted that since the hooks are resilient, the loops C and B are permitted to be drawn through the restricted entrances to the pockets 8 and 14. 20 After becoming seated or placed in the latter, the inherent resiliency of the hooks causes the arms thereof to assume their original positions, thus rendering the entrances to the pockets too small to permit the hooks to become accidentally disengaged from said loops. This being the case, the hooks practically become a permanent part of the hame and there is no chance of the 25 fastener becoming lost or displaced when the hame is taken off of the collar E. Attention is directed to the fact that when the hame is on the collar as disclosed in Figure 1, the flared ends of the hooks rest against the adjacent portion of the collar. Since 30 the ends of the hooks extend a considerable distance beyond the loops which they engage, there is little possibility of the hooks rotating in such a manner as to become accidentally disengaged from said loops. It 35 may also be pointed out at this point that when the strap is tightened to its full degree, the free ends of the hook tend to move toward the opposite or connected ends thereof and thus decrease the size of the already restricted entrance of the pocket. Hence, 40 there is no possible way in which the hooks can become accidentally displaced or disengaged from said loops. While this particular construction of the hooks is sufficient to 45 normally retain them in their respective loops, it is also such that it permits quick and easy detachment of the hooks from the loops after the hame is removed from the 50 collar.

From the foregoing description, it will be seen that I have devised an extremely efficient and simple connection for the lower ends of the hame section, the same consisting of a pair of resilient hooks that can be snapped into proper existing pivoted loops on the hame section and the construction of these hooks being such that they become a permanent part of said sections unless 55 moved by force. The hooks can be easily

and readily engaged with said loops owing to the flared ends with which they are equipped and which serve to facilitate such connection. An extremely important feature is, as before stated, the fastener composed of extremely few parts which enables me to manufacture the same at a very low cost, this being due to the fact that the amount of leather employed in the make-up of the fastener is reduced to a minimum and it becomes unnecessary to employ any special buckles or the like, since the conventional buckles now on the market may be used. These, and other advantages and features of the invention have, no doubt, become apparent from the foregoing description and drawings. In view of this, a more lengthy description with particular details and use of the fastener is thought unnecessary. 80 85 90 95 100 105 110 115 120 125 130

Since probably the best results may be obtained with the construction and arrangement herein shown and described, this construction and arrangement is taken as a preferred embodiment of the invention. However, slight minor changes coming within the scope of the subjoined claims may be resorted to if desired.

I claim:

1. A hame fastener comprising a pair of resilient hooks for permanent engagement with the usual loops on the lower ends of the hame sections, the free ends thereof being flared to facilitate engagement thereof with said loops, said ends when in use bearing against the collar and prevent possible disengagement of the hooks from the loops, a strap carried by one hook, and a co-acting buckle for the latter carried by the remaining hook. 105

2. The combination with a horse collar having a hame thereon; of a fastener for the lower ends of the hame sections, including a pair of resilient hooks, each formed from a strip of metal bent upon itself to form a substantial U, thereby providing a pocket intermediate its ends for reception of the usual pivoted loops on the lower end of the hame sections, the strips beyond said pockets being provided with transverse inwardly projecting portions, providing restricted entrances for said pockets the free ends of said hooks bearing against said collar to prevent possible displacement of said hooks from said loops, a strap carried by one hook, and a buckle carried by the remaining hook. 110 115 120 125

3. A hame fastener comprising a strap, a link carried thereby, a strip of resilient metal passed through said link, having its ends brought together around the latter and being bent upon itself to form a substantially U-shaped hook, the free end of the latter being flared to facilitate engagement with a loop on the lower end of one of the hame sections said free end overlying and 130

extending beyond said link and being intended to bear against the collar when in use, the intermediate portion of said hook constituting a pocket for reception of said loop and the hook beyond the pocket having a transverse inward depression which serves to provide a restricted entrance for the

10 pocket, a second hook for connection to the loop on the remaining lame section, and a buckle carried by said last named hook for co-action with said strap.

In testimony whereof I have hereunto set my hand.

SAMUEL CARL STIMSON.
